CONSTANT LEVERAGE ENGINE

Jacob Riederer, Stowe, Vt.

Application September 17, 1949, Serial No. 116,288

8 Claims. (Cl. 74—44)

1

This invention relates to a gear type crank shaft arrangement for reciprocating type engines.

It is an object of the present invention to provide a gear type crank shaft arrangement for reciprocating engines wherein maximum power effect on the power stroke of the piston is had throughout the full stroke of the piston and of the piston rod, the full downward stroke of the piston and of the operating gear acting with maximum effect upon the crank shaft gear, the connecting rod acting in a straight line throughout the full length of the piston stroke.

It is another object of the present invention to provide a gear type crank shaft arrangement wherein the downward stroke of a piston effects the operation of the crank shaft while the connecting rod is kept in a vertical position throughout the full length of the stroke wherein relief or a turn of the actuating gear is effected by rotation and by the slippage of the operating gear upon its pivot connection, there being a slot through the gear to permit the working of the operating gear upon the pivot connection of the same and wherein the operating gear is so shaped that the opposite sides of the gear are used for successive strokes of the piston in the downward direction and the end and rounded ends of the gear are used for the return stroke of the piston, the fulcrum lever action being effected upon the operating gear on the return stroke of the piston.

Other objects of the present invention are to provide a gear type crank shaft arrangement for reciprocal engines which is of simple construction, inexpensive to manufacture, easy to assemble, has a minimum number of parts, compact and efficient in operation.

For other objects and for a better understanding of the invention, reference may be had to the following detailed description taken in connection with the accompanying drawing, in which

Fig. 1 is a longitudinal sectional view of a reciprocating engine employing the gear type crank shaft arrangement of the present invention.

Fig. 2 is a vertical sectional view of the engine taken on line 2—2 of Fig. 1.

Fig. 3 is a similar sectional view after the piston has been lowered to the bottom of the cylinder.

Fig. 4 is a sectional view similar to Fig. 2 with the piston starting its return stroke.

Fig. 5 is a sectional view similar to Fig. 2 after the piston has been advanced to near the end of its return stroke.

Fig. 6 is a fragmentary end elevational view of the crank shaft arrangement.

2

Fig. 7 is a detail sectional view taken on line 7—7 of Fig. 6.

Fig. 8 is a detail sectional view taken on line 8—8 of Fig. 2.

5 Fig. 9 is a perspective view of the reciprocating engine with portions broken away and looking upon the gear crank shaft arrangement.

Referring now to the figures, 10 represents a cylinder block having the usual cylinder chambers 11 therein in which operates pistons 12. The cylinder block has a stub shaft 13 extending from its forward end on which is rotated the usual fan 14 for causing a flow of air through a forward radiator 15. On the fan is a pulley 16 over which passes a fan belt 17 that drives a generator 18. This fan belt is driven by a pulley 19 on the end of a driving shaft 21 that extends through crank case 22. This shaft 21 extends through the rear of the crank case 22 and carries a fly wheel 23 which will be continually rotated by the engine. The shaft can be connected to the driving gear of a vehicle or to any other output or propeller shaft by which power is transmitted.

25 25 Depending from the cylinder block into the crank case 22 is a plurality of depending brackets 24, one bracket being adjacent to each cylinder. The lower end of the bracket has an enlargement 25 with a stub pin 28 therein. This pin 28 extends through a slot 29 in an operating gear 31. The operating gear has straight gear sides 32 and 33 and rounded end gear portions 34. Each of these gears 31 are meshed with a round gear 35 which is fixed to shaft 21 running through the crank case. Shaft 21 is supported on a bracket 36. There are a plurality of these brackets also depending from the cylinder block and preferably connected with the lower end of the bracket 24, as shown more clearly in Fig. 6.

30 40 If desired, as shown in Fig. 6, the bracket 24 may contain a guide 37 on which moves a slide 38, Fig. 7. The slide has a pin 39 to which connecting rod 41 is connected to effect a driving action upon the operating gear 31.

45 45 Piston rod 41 may be curved as shown in the figures so that on the return movement of the operating gear a maximum angular displacement of the connecting rod 41 can be had without the connecting rod striking the bottom edge of the cylinder wall. The lower end of the connecting rod is journalled upon the center of the operating gear 31. As shown in Fig. 2, the movement of the piston causes direct downward displacement of the gear 31 so that one of its sides 32 or 33 causes 50 55 the rotation of the gear 35. As long as the stroke

is continued in the vertical downward direction, the straight side of the gear is being used upon the gear 35. In Fig. 3, the piston 12 is shown in its downward position and the gear 31 remains vertical. As the return stroke of the piston 12 starts, the gear 31 will pivot about the pin 28 and the rounded portion 34 of the gear will act upon the gear 35. The movement of the rounded portion 34 upon the gear continues until the piston 12 has been elevated to its fully raised position and upwardly of the position shown in Fig. 5 whereby to locate the other straight side of the actuating gear 31 preparatory to the operation of the next power and downward stroke. It can be seen that the leverage acting upon the shaft 21 remains constant throughout the full extent of the power stroke. The gear 31 is fulcrumed to effect the return or the upward movement of the gear. During the return stroke, the connecting rod moves outwardly at its lower end to give maximum turning action upon the gear 31 during this return stroke.

The gear teeth are preferably of the herring bone type whereby to eliminate any tendency for the gears to slide from one another and to eliminate side thrust. The form of the invention as shown in Fig. 6 is slightly different from the invention as shown in the other figures, the principle of operation being fundamentally the same. On each gear 31 is a transverse portion 43 in which is pin 44 to which the connecting rod 41 is attached. The transverse portion 43 is sufficiently spaced from the slot 24 as to permit the sliding of the gear over the pin 28.

It will now be apparent that the lever arm which is effective upon the turning of the shaft 21 is constant throughout the complete downward stroke of the piston. It should be further apparent that upon the return stroke of the piston, the gear is pivoted to position the opposite side of the same for the next downward stroke.

While various changes may be made in the detail construction, it shall be understood that such changes shall be within the spirit and scope of the present invention as defined by the appended claims.

Having thus set forth and disclosed the nature of my invention, what is claimed is:

1. A reciprocating engine comprising a cylinder block having a cylinder opening therein, a crank case supporting said cylinder block, a drive shaft extending through the crank case, a gear fixed to said drive shaft, a piston operable in said cylinder opening, an operating gear engaging with the gear on said shaft, said operating gear having straight sides and rounded ends, a connecting rod pivotally connected to the piston at one end and to the operating gear at the other end centrally of the operating gear and means for slidably connecting the operating gear to the cylinder block for rotational movement with respect thereto.

2. A reciprocating engine comprising a cylinder block having a cylinder opening therein, a piston adapted to work in said cylinder opening, a crank case supporting said cylinder block, a shaft extending through the crank case from one end to the other, a gear on the shaft, an operating gear having two straight sides and rounded ends engaging with said gear on the shaft, a connecting rod between the piston and the operating gear whereby upon the downward stroke of the operating gear rotation of the gear on the shaft is effected during the power stroke without a change in the effective lever arm, said cylinder block hav-

ing a depending bracket, a pin fixed upon the depending bracket, said operating gear having a slot receiving said pin whereby the operating gear can be rotated when the pin is at the upper end of the slot.

3. A reciprocating engine comprising a cylinder block having a cylinder opening therein, a piston adapted to work in said cylinder opening, a crank case supporting said cylinder block, a shaft extending through the crank case from one end to the other, a gear on the shaft, an operating gear having two straight sides and rounded ends engaging with said gear on the shaft, a connecting rod between the piston and the operating gear whereby upon the downward stroke of the operating gear rotation of the gear on the shaft is effected during the power stroke without a change in the effective lever arm, said cylinder block having a depending bracket, a pin fixed upon the depending bracket, said operating gear having a slot receiving said pin whereby the operating gear can be rotated when the pin is at the upper end of the slot, and said connecting rod being of curved shape to permit the pivoting of the operating gear without the interference of the cylinder block.

4. In a multiple piston reciprocating engine comprising a cylinder block having a plurality of cylinder openings, pistons workable in said opening, a crank case supporting said cylinder block, a plurality of depending brackets on the cylinder block, pivot pins fixed to the end of the depending brackets, operating gears having straight sides and rounded ends and a slot receiving the pivot pins, there being a gear for each pivot pin, a shaft extending longitudinally through the gear casing and having respectively gears therein meshing with the operating gears, and connecting rods pivotally connected respectively to the working pistons and to the respective operating gears.

5. A reciprocating engine comprising a cylinder block having a cylinder opening therein, a crank case supporting said cylinder block, a drive shaft extending through the crank case, a gear fixed to said drive shaft, a piston operable in said cylinder opening, an operating gear engaging with the gear on said shaft, said operating gear having straight sides and rounded ends, a connecting rod pivotally connected to the piston at one end and to the operating gear at the other end centrally of the operating gear, and means for slidably connecting the operating gear to the cylinder block to permit the rotation of the operating gear on its return stroke, and said gears having gear teeth of the herring bone type to eliminate side thrust of the gears with respect to one another.

6. In a multiple piston reciprocating engine comprising a cylinder block having a plurality of cylinder openings, pistons workable in said opening, a crank case supporting said cylinder block, a plurality of depending brackets on the cylinder block, pivot pins fixed to the end of the depending brackets, operating gears having straight sides and rounded ends and a slot receiving the pivot pins, there being a gear for each pivot pin, a shaft extending longitudinally through the gear casing and having respectively gears therein meshing with the operating gears, and connecting rods pivotally connected respectively to the working pistons and to the respective operating gears, and said connecting rods being of curved shape to prevent the interfer-

ence of the connecting rod with the lower end of the cylinder opening.

7. A reciprocating engine comprising a housing, said housing having a cylinder opening therein, a piston workable in said cylinder opening, a shaft extending through the housing, a gear on said shaft, an operating gear having straight sides and rounded ends meshing with the gear on the shaft to drive the same, a connecting rod between the piston and the operating gear and pivotally connected with the operating gear, a pivot pin carried on the housing, said operating gear having an elongated slot receiving the pivot pin on the housing whereby to permit the rotation of the operating gear over the rounded ends of the same, the straight sides of the operating gear being used with the stroke of the piston.

8. A reciprocating engine having a cylinder opening therein, a piston workable in said opening, a bracket having a guide portion, a slide on said bracket, a connecting rod connected between the piston and the slide, a shaft journaled in the engine, a driving gear connected to the shaft, an operating gear connected to said slide and having straight sides and rounded ends and engaging with the gear on the shaft, said operating gear being adapted to pivot on said slide at the end of its downward stroke to present the gear teeth on the rounded end with the gear on the shaft and to effect the reversal of the operating gear to place its opposite side in mesh with the gear on the shaft.

JACOB RIEDERER.
